CLAIM

The ornamental design for a snap fastener element, as shown and described.

DESCRIPTION

FIG. 1 is a perspective view of a snap fastener element showing my new design;

FIG. 2 is a top plan view;

FIG. 3 is a side elevational view;

FIG. 4 is a bottom plan view;

FIG. 5 is an enlarged sectional view taken on the line 5—5 of FIG. 2;

FIG. 6 is a perspective view of snap fastener element showing the female modification of my new design;

FIG. 7 is a top plan view of the modification;

FIG. 8 is a side elevational view of the modification;

FIG. 9 is a bottom plan view of the modification; and

FIG. 10 is an enlarged sectional view taken on the line 10—10 of FIG. 7.
